CLAIM

The ornamental design for a tilted front console for a cooking appliance, as shown and described.

DESCRIPTION

FIG. 1 is a top perspective view of a tilted front console for a cooking appliance, according to a claimed design;

FIG. 2 is a front elevation view thereof;

FIG. 3 is a first side elevation view thereof;

FIG. 4 is a second side elevation view thereof;

FIG. 5 is a top plan view thereof;

FIG. 6 is a bottom perspective view thereof;

FIG. 7 is a back perspective view thereof;

FIG. 8 is a partial enlarged top perspective view of area 8 indicated in FIG. 1;

FIG. 9 is a partial enlarged front elevation view of area 9 indicated in FIG. 2;

FIG. 10 is a partial enlarged first side elevation view of area 10 indicated in FIG. 3;

FIG. 11 is a partial enlarged second side elevation view of area 11 indicated in FIG. 4;

FIG. 12 is a partial enlarged top plan view of area 12 indicated in FIG. 5;

FIG. 13 is a partial enlarged bottom perspective view of area 13 indicated in FIG. 6; and,

FIG. 14 is a partial enlarged back perspective view of area 14 indicated in FIG. 7.

The portions of the article shown in even broken line form no part of the claimed design. Dash-dot lines adjacent un-shaded areas represent bounds of the claimed design and
